ELECTRIC LAMP

Estell M. Watson, Cleveland Heights, Ohio, assignor to General Electric Company, a corporation of New York

Application November 29, 1933, Serial No. 700,267

7 Claims. (Cl. 176—32)

My invention relates to electric lamps and similar devices comprising an electric energy translation element, such as a filament, sealed in a bulb.

5 Heretofore, the practice has been to provide a separate base for such devices which is cemented to the closed neck of the bulb, the "mount," comprising the energy translation element and its supporting structure, being supported by the bulb.

10 According to my invention, a metal base is sealed directly to the open neck of the bulb, thus actually constituting a portion of the bulb wall, and the mount is supported by the said metal base independently of the glass bulb. The said base is

15 provided with engagement means for mounting the lamp in a socket and is especially adaptable for precision lamps, in which the light source, or filament, must bear a definite predetermined relation to the base. The present practice consists

20 in mounting the filament in the bulb and then attaching the base to the bulb so that it is accurately located with respect to the filament. According to the present invention the filament is accurately mounted directly on the base so that it

25 bears a definite predetermined relation to the engagement means on said base, after which the bulb is sealed to the base. The lamp can be used to advantage in projectors comprising a reflector or lens with respect to which the filament must

30 be accurately located, since standard lamps made according to my invention may be interchanged without the necessity of focusing adjustments. Further features and advantages of my invention will appear from the following detailed description thereof and from the drawing.

35 In the drawing, Fig. 1 is a perspective view of an incandescent electric lamp of my invention; Fig. 2 is a longitudinal section therethrough; Fig. 3 is a transverse section through said lamp along line 3—3 of Fig. 2; Fig. 4 is a longitudinal section through a modified lamp of my invention; Fig. 5 is a transverse section through said modification along line 5—5 of Fig. 4; and Fig. 6 is a perspective view partially in section of a socket suitable for use with the lamp of my invention.

40 Referring now to the drawing and particularly to the lamp illustrated in Figs. 1, 2 and 3, said lamp comprises a filament 10 the ends of which are mounted on lead wires 11 and 12 in the bulb 13. The opposite ends of each of the lead wires are mounted on separate conductive portions of the base 14. The base comprises a metal ring 15 having a pair of oppositely disposed flanges or lugs 16 and 17 extending therefrom and an inwardly extending lug or lip 18 to which lead wire

12 is welded, and a disc 19 which is attached to said ring 15 by a collar or ring 20 of glass and which is welded to lead wire 11. The ring 15 and disc 19 are of a metal or alloy which has substantially the same coefficient of expansion as the glass parts sealed thereto. One such alloy which also "wets" well to the glass consists substantially of 73 per cent iron and 27 per cent chromium. The base flanges are preferably of different width and in this instance have been stiffened by a downwardly bent flange 21. The glass collar 20 of the base serves to facilitate attachment of the bulb 13 to the base as the neck thereof is sealed to said collar, and also serves to support the filament 10 by means of a plurality of wires 22 partially embedded therein and extending upward and engaging intermediate sections of said filament. The lamp is preferably exhausted through aperture 23 in disc 19 which is then closed by a body 24 of glass sealed thereto.

20 The modification of my invention shown in Figs. 4 and 5 comprises a bulb 25 in which is mounted, between lead wires 26 and 27, the filament 28. The wires 26, 27 extend upward from the base 29. The wire 26 is welded to a metal ring 30 which is provided with a pair of oppositely disposed and outwardly extending flanges or lugs 31 and 32 and which is sealed to the neck of the bulb 25 as shown. The wire 27 is welded to disc 33 which is sealed to a collar or ring 34 of glass which is also sealed to ring 30. The intermediate portions of the filament are supported by a plurality of wires 35 extending from a glass arbor 36 which preferably is attached to an inwardly and upwardly extending lug or lip 37 on ring 30. The lamp is evacuated through aperture 38 in disc 33 which is then closed by a mass 39 of glass sealed thereto.

25 A socket suitable for either of the lamps described is shown in Fig. 6. This device consists of an insulating body 40 in which is mounted a metal shell 41 and a pin 42, each of which constitutes a terminal element. The shell is provided with a recessed portion or annular shoulder 43 and a pair of flanges 44 and 45 so disposed as to provide unequal openings therebetween of substantially the same size as the lamp base flanges. Each of the flanges 44, 45 is provided with a downwardly extending lip 46 which prevents the base from being turned counterclockwise after insertion and with depressed portions 47 which lock the base flanges in place after they have been inserted thereunder by a clockwise rotation of the lamp. Pin 42 engages the base disc and is urged upward against the bottom of said

disc by spring 48. To insert the lamp in the socket, it is advanced toward said socket so that the base flanges are brought opposite the proper openings between the socket flanges 44, 45 whereupon the said lamp is pushed downward and turned clockwise until the base flanges are located behind the depressed portions 47 of said socket flanges. In this position, the base flanges engage the lower surface of the socket flanges between lip 46 thereof and depression 47, and the disc of the lamp base is in engagement with pin 42.

What I claim as new and desire to secure by Letters Patents of the United States is:

1. An electric lamp or similar device comprising a bulb, a base comprising a metal ring portion sealed to the walls of an opening in said bulb and having engagement means for mounting said lamp and a metal disc sealed to said ring portion over said opening in said bulb through the medium of an insulating collar of plastic material, an energy translation element in said bulb, a pair of leading-in wires each connected at one end to one end of said translation element, the opposite ends of said leading-in wires being attached respectively to said ring and disc portions of said base.

2. An electric lamp or similar device comprising a bulb, a base comprising a metal ring portion sealed to the walls of an opening in said bulb and having engagement means for mounting said lamp and a metal disc sealed to said ring portion through the medium of an insulating collar of plastic material, an energy translation element in said bulb, a pair of leading-in wires each connected at one end to one end of said translation element, the opposite ends of said leading-in wires being attached respectively to said ring and disc portions of said base, and a plurality of support wires engaging portions of said translation element and having their ends embedded in said insulating collar.

3. An electric lamp or similar device comprising a bulb, a base comprising a metal ring portion sealed to the walls of an opening in said bulb and having engagement means for mounting said lamp and an inwardly extending lug and a metal disc sealed to said ring portion over said opening in said bulb through the medium of an insulating collar of plastic material, said lug projecting into said bulb through said insulating collar, an energy translation element in said bulb, and a pair of leading-in wires each connected at one end to one end of said translation element, the opposite ends of said leading-in wires being attached respectively to said inwardly projecting lug and disc portions of said base.

4. An electric lamp or similar device comprising a bulb, a base comprising a metal ring portion sealed to the walls of an opening in said bulb and having laterally and outwardly extending

engagement means for mounting said lamp and a metal disc sealed to said ring portion over said opening in said bulb through the medium of an insulating collar of plastic material, an energy translation element in said bulb, and a pair of leading-in wires each connected at one end to one end of said translation element, the opposite ends of said leading-in wires being attached respectively to said ring and disc portions of said base.

5. An electric lamp or similar device comprising a bulb, a base comprising a metal ring portion sealed to the walls of an opening in said bulb and having laterally outwardly extending engagement means and a lug extending inwardly into said bulb and a metal disc sealed to said ring portion through the medium of an insulating collar of plastic material, an energy translation element in said bulb, a pair of leading-in wires each connected at one end to one end of said translation element, the opposite ends of said leading-in wires being attached respectively to said inwardly extending lug and disc portions of said base, an insulating arbor mounted on said lug and extending upwardly in said bulb, and a plurality of support wires mounted on said arbor and engaging portions of said energy translation element.

6. An electric lamp or similar device comprising a bulb, a base comprising a metal terminal ring portion sealed to the walls of an opening in said bulb and having engagement means for mounting said lamp and a metal terminal disc sealed to said terminal ring portion over said opening in said bulb through the medium of an insulating collar of fusible material, said terminal disc constituting the end wall of the bulb, an energy translation element in said bulb, and a pair of leading-in wires each connected at one end to one end of said translation element, the opposite ends of said leading-in wires being attached respectively to said ring and disc portions of said base.

7. An electric lamp or similar device comprising a bulb, a base comprising a metal terminal ring portion sealed to the walls of an opening in said bulb and having engagement means for mounting said lamp and a metal terminal disc sealed to said terminal ring portion over said opening in said bulb through the medium of an insulating collar of fusible material, said terminal disc constituting the end wall of the bulb, an energy translation element in said bulb, and a pair of leading-in wires each connected at one end to one end of said translation element, the opposite ends of said leading-in wires being attached respectively to said ring and disc portions of said base, and at least one support wire engaging a portion of said translation element and having its end embedded in said collar.

ESTELL M. WATSON.
